SPOON OR SIMILAR ARTICLE

William S. Warren, Meriden, Conn., assignor to
R. Wallace & Sons Manufacturing Company,
Wallingford, Conn., a corporation of Connecticut

Application March 6, 1952, Serial No. 18,791

Term of patent 14 years

(Cl. D54—12)

To all whom it may concern:

Be it known that I, William S. Warren, a citizen of the United States of America, residing at Meriden, county of New Haven, and State of Connecticut, have invented a new, original, and ornamental Design for a Spoon or Similar Article, of which the following is a specification, reference being had to the accompanying drawing, forming part thereof.

In the drawing:

Fig. 1 is a front elevational view of a spoon, showing my new design; and

Fig. 2 is a rear elevational view thereof.

I claim:

The ornamental design for a spoon or similar article, substantially as shown.

WILLIAM S. WARREN.
